UNITED STATES PATENT OFFICE.

HOMER D. WILLIAMS AND WILLIAM AHLEN, OF DUQUESNE, PENNSYLVANIA.

GAS-WASHING PLANT.

1,037,095.

Specification of Letters Patent.

Patented Aug. 27, 1912.

Application filed April 7, 1909. Serial No. 488,480.

To all whom it may concern:

Be it known that we, HOMER D. WILLIAMS and WILLIAM AHLEN, both of Duquesne, Allegheny county, Pennsylvania, have invented a new and useful Gas-Washing Plant, of which the following is a full, clear, and exact description, reference being had to the accompanying drawings, forming part of this specification, in which—

10 Figure 1 is a plan view showing a gas washing plant constructed and arranged in accordance with our invention; Fig. 2 is a sectional end elevation on a larger scale, taken on the irregular line II—II of Fig. 1; 15 showing the gas scrubber and the connections leading into and out of the gas scrubbers and showing the means employed for controlling the flow of gases into and out of the scrubbers; Fig. 3 is a transverse sectional 20 elevation on the line III—III of Fig. 2 showing the construction of the bottom portion of the scrubbers; Fig. 4 is a sectional end elevation on a larger scale, taken on the line IV—IV of Fig. 1 showing the means 25 employed for further cleaning the gases and for causing the gases to flow from one gas main to the other, Fig. 5 is a similar sectional end elevation taken on the line V—V of Fig. 1, showing the rotary gas washers 30 and the gas mains having connections leading to and from the gas washers; Fig. 6 is a plan, on a larger scale, with parts broken away, showing the details of the connections between the gas-mains and the scrubbers, the fans and the rotary gas washers of Fig. 1; Fig. 7 is a half horizontal section, 35 on a larger scale taken on the line VII—VII of Fig. 4; Fig. 8 is a half horizontal section taken on the line VIII—VIII of Fig. 5; 40 Fig. 9 is a detail section on a larger scale, showing the corrugations on the inside surfaces of the centrifugal separators of Figs. 4, 5, 7 and 8; Fig. 10 is a sectional plan showing the vertically extending partition 45 in the combined water sealing valve and dust catcher used in connection with the gas washing plant.

Our invention relates to apparatus for handling and cleaning gases of their impurities, and more particularly relates to apparatus used in handling and cleaning blast furnace gases, to remove the finely divided solid materials usually carried in suspension in such gases from the blast furnaces in which the gases are generated.

One object of the invention is to provide

a gas washing plant having improved means for conducting and washing the gases.

Another object of our invention is to provide improved means for bringing the gases 60 into contact with water or other fluid, for separating the fluid and the scrubbed gases, and for removing entrained fluid or moisture from the gases after being subjected to the cleaning action of water or other fluid. 65

In the drawings, 2, 2 represents a pair of blast furnaces having downcomers 3, 3, leading into dry dust catchers 4, 4. The dust catchers 4 are preferably connected by means of the pipes 5, 5, with duplicate dry 70 dust catchers 6. The dust catchers 6 are directly connected by the pipes 7 to the gas mains 9 which lead to the hot blast stoves 10 of the respective furnaces 2, branch pipes 11 being provided on the gas mains 9, which 75 connect with independent gas burners, (not shown) for the hot blast stoves 10. A suitable valve 8 is located on each of the pipes 7 to shut off the supply of gas to the gas burners through these pipes. The dust 80 catchers 6 are also connected by means of branch pipes 12 with the gas main 13 for the rough gas leading to the primary washers or gas scrubbers 14. Suitable valves 15 which when open act as dust catchers are 85 provided for shutting off the supply of gas to the main 13 from either of the branch pipes 12, when desired. Each valve 15 also serves as a dust catcher when not containing sufficient water to shut off the gas supply to the main 13 from its branch pipe 12. 90

Connected to the rough gas main 13 by branches 16 and 17, is a series of gas scrubbers 14, a combined dust catcher and gas valve 18, similar to the valve 15, being located between the branches 16 and 17 leading into each scrubber, and a suitable damper valve 19 is also provided on the branches 16 leading to each of the scrubbers 14 for the purpose of shutting off the supply of gas from its particular scrubber. The valves 15 and 18 have depending partitions 15^a and 18^a and have water overflow openings 15^b and 18^b which are located above the lower edge of the partitions 15^a, 105 18^a to shut off the flow of gas when supplied with water through the water inlet pipes 15^c and 18^c. The bells on the bottom of the valves 15 and 18 are lowered to empty the water from the valves and also in removing 110 accumulations of flue dust collected therein when the valves are used as dust catchers.

The top portion of each scrubber is provided with an outlet pipe 20 through which the scrubbed gas is conducted from the scrubbers into the gas main 21. The gases 5 enter the lower portion of the scrubbers 14 and rise upwardly through the scrubber chambers, passing into the branches 20. A water inlet pipe 14^a having spraying arms 14^b which may or may not be rotated as is desired is provided in the top portion of each scrubber for supplying water to the chamber and scrub the gases, the water and gases passing through the scrubber in opposite directions. A screen or grid 14^c is provided at 10 the upper portion of the scrubber 14 to break up the entering water into drops which descend through the scrubber in a rain. The bottom portion of the scrubber 14 is provided with a curved pipe 14^d having its ends elevated above the center of its length so as to form a water-sealed trap or drain outlet through which the used water is drained from the bottom of the scrubber and the flue dust or other solid materials 15 removed from the gases by contact with the water are washed from the scrubbers. A deflector 14^e is located at the bottom of the scrubber 14 above the gas inlet pipe 17 to direct the gases upwardly in entering 20 the scrubber. The branch pipe 20 on each of the scrubbers is provided with a mushroom valve 22, by which the entrance of gas from its scrubber into the pipe 21 is regulated and controlled.

25 The scrubbed gases entering the gas main 21 pass through the gas main and descend downwardly through the series of vertical legs or branches 23 into the enlarged bottom portion 24 of these legs from which the 30 gases are lead through the branch pipes 25 into the fans 26. The gases coming from the scrubbers 14 have been partially cleaned and cooled by the drenching rain of water or other fluid to which they are subjected in 35 the scrubbers, and the gases will come from the scrubbers in a more or less saturated condition, and will also contain a considerable amount of entrained moisture due to the rapid flow of the gases. The gases, 40 when passing through the fans 26 are further separated from entrained moisture and from any flue dust remaining therein by the centrifugal action of the fans. The fans 26 which may be either of the several 45 known types now obtainable also serve to increase the pressure of the gas so as to successfully convey the same through the later gas mains which are of greater or less length and lead to the stoves, boilers, or to 50 the additional cleaners or washers, when the gases are subjected to further cleaning operations.

55 The enlarged portions 24 of the down legs 23 on the gas main 21 are provided 60 with water overflow outlets 27, and are also

provided with a water supply pipe 24^a having a valve 24^b for supplying water to the enlarged leg 24. The bottom portions of the legs 24 are provided with drain pipes 28, which extend from the legs 24 into the sealing pool located beneath the fans 26. The end of the pipes 28 project downwardly below the level of the fluid in the pool so as to maintain a water seal for the gases when the valves 29 on the pipes 28 are open as 70 they are when the passage of gases through the apparatus is desired. The fans 26 also are provided with drain pipes 30, which project downwardly below the level of the fluid in the pool 31 and form water seals 75 to prevent escape of the gases through these pipes. The fans 26 are also provided, when desired, with water pipes 26^a through which water is supplied when required for further cooling or cleaning of the gases or 80 to clean the fan in case the fan blades should become coated with flue dust or other solid particles removed from the gases. The fans 26 are connected by means of the branches 32 with the top portions of the vertical chambers 33. These chambers act as combined separators and water-sealing valves, water supply pipes 33^a being provided to supply water to the chambers 33. The pipes 32 are provided with butterfly valves 85 34 by which the volume of gases flowing through each fan is regulated.

90 The gases carry along some entrained moisture and some finely divided solid particles also remain in the gases even after 100 having passed through the fans. When water is added in the fans, the entrained moisture is largely in the form of mist, and when considerable quantities of moisture in the 105 form of mist is mixed with the gases the mixture is rendered very unsuitable for heating or for use in gas engines, as the combined heat value is then low and the gases in such condition ignite and burn with great difficulty.

110 In order to remove an excessive amount of moisture together with any dirt still remaining in the gases, the separator chambers 33 are constructed as shown in Fig. 4 so as to compel the gases to flow downwardly 115 through the chambers in a helical path, and, by reason of the fans 26, travel at a high velocity, the gases entering the separators tangentially at the top and leaving the separator chambers 33 through the centrally located risers or branch pipes 35', then rising upwardly through the branches 35 and entering the gas main 36.

120 The tangential force of the gases passing in a helical path through the separators 33 causes the water and the heavier particles in the gases to be thrown outwardly against the outer surfaces of the separators. These outer walls or surfaces are preferably made grooved or corrugated as shown in the 125 130

drawings so as to present a larger surface to the gases for securing the deposited moisture and dirt. The bottom portion of the chambers or separators 33 are provided with drain pipes 37, which terminate in a water sealing pool, and through which the water and dirt is automatically drained from the chambers 33. The pipes 37 are provided with valves 38, which are normally open, but which may be closed when required to shut off the escape of gas from the chambers 33 or the entrance of air into these chambers in cases where the water is removed from the pool 31 for any purpose. The chambers 33 are also provided with water overflow outlets 39 and with water inlets 33^a, by which water is added to the chambers, when desired. By closing the valves 38 and permitting the water to flow into the chambers 33, the level of the water will rise above the bottom portion of the central chambers or risers 35 so as to provide water seals and prevent flow of gases from the chambers 33 into the risers 35.

25 The gases on reaching the gas main 36 are clean enough for ordinary uses, such as for burning under boilers or in the combustion chambers of the hot blast stoves, and the pipe 36 is connected by branch pipes 36^a 30 with the gas supply mains 9 for the hot blast stoves, a suitable shut-off valve 36^b being provided on each branch pipe 36 to shut off the supply of gas when required.

When the gases are to be used in supplying fuel to gas engines, it will be desirable to subject them to a further cleaning action in order to remove any slight amount of solid material still remaining in suspension in the gases. In order to furnish a supply 40 of gases in a condition suitable for use in gas engines a gas main 40 is provided which leads to the gas engines and which is connected by means of suitable branches 40' with the series of rotary gas cleaners 41, 45 these cleaners being connected by the branch pipes 42 with the clean gas main 36.

The gas main 36 is connected by the vertical down legs 43 with the branches 40', suitable valves 44 being provided to shut 50 off each branch 40' from the gas main 36. The branches 40' lead into the rotary washers 41, which preferably are of the type of rotary gas washer shown in Patent No. 704,593, the gases passing through these 55 washers and rising through the bent branch pipes 42, enter tangentially into the enlarged chambers 45, and pass, in a helical path downwardly and then upwardly through the risers 47, forming an extension 60 to the branch pipes 46, which lead into the gas main 40 leading to the gas engines pipes 46, the action in separating the gases and impurities in this chamber 45 being the same as that described for the chamber 33.

65 A shut-off valve 48 is provided on the

branch pipes 46 at a point just above the top of the enlarged chambers 45 for the purpose of shutting off either branch pipe 46 from its fan and from its enlarged chamber 45 and the rotary washer. The gas 70 mains 20, 36 and 40 are provided with suitable relief valves 49 at intervals in their length which open automatically when the pressure in the gas mains becomes excessive, in this way preventing danger of damage 75 from high pressures or explosions occurring in the gas mains.

The advantages of our invention will be apparent to those skilled in the art. By means of our improved gas-washing plant, 80 a flexible apparatus is provided by which the washing of the gases can be carried out in an economical and efficient manner and by which the degree to which the washing operation is carried out can be varied. The 85 apparatus is provided with means for operating the plant as a whole, or the plant can be regulated to vary the portions of the apparatus in use to suit the amount of gas being provided to be washed. Means for 90 shutting off part or all of the different portions of the apparatus are provided to facilitate repairs, and for preventing waste in power and water, or other fluid used in washing the gases.

95 Modifications in the construction and arrangement of the apparatus may be made without departing from our invention.

We claim:—

1. A gas washing plant comprising a plurality of gas scrubbers, a plurality of cleaning fans, and a plurality of centrifugal gas cleaners, a gas supply main connecting a source of gas supply with the scrubbers, a gas supply main connecting the scrubbers 100 with the rotary fans, a third gas main connecting the fans with the centrifugal gas cleaners, said main also having connections leading to a point of use for the scrubbed and cleaned gases, a fourth gas main connecting the centrifugal washers with a source of use, and means whereby the flow of gases from one main to the other is regulated and controlled.

110 2. A gas washing plant comprising a plurality of gas scrubbers, a plurality of cleaning fans, and a plurality of centrifugal gas cleaners, a gas supply main connecting a source of gas supply with the scrubbers, a gas supply main connecting the scrubbers 120 with the rotary fans, a third gas main connecting the fans with the centrifugal gas cleaners, said main also having connections leading to a point of use for the scrubbed and cleaned gases, a fourth gas main connecting the centrifugal washers with a source of use, and means whereby the flow of gases into each centrifugal washer is regulated and shut off.

125 3. A gas washing plant comprising a plu- 130

rality of gas scrubbers, a plurality of cleaning fans, and a plurality of centrifugal gas cleaners, a gas supply main connecting a source of gas supply with the scrubbers, a 5 gas supply main connecting the scrubbers with the rotary fans, a third gas main connecting the fans with the centrifugal gas cleaners, said main also having connections leading to a point of use for the scrubbed 10 and cleaned gases, a fourth gas main connecting the centrifugal washers with a source of use, means whereby the flow of gases into each centrifugal washer is regulated and shut off, and means whereby the 15 inlet and outlet openings to each cleaning fan is closed.

4. A gas washing plant comprising a plurality of gas scrubbers, a plurality of cleaning fans, and a plurality of centrifugal gas 20 cleaners, a gas supply main connecting a source of gas supply with the scrubbers, a gas supply main connecting the scrubbers with the rotary fans, a third gas main connecting the fans with the centrifugal gas 25 cleaners, said main also having connections leading to a point of use for the scrubbed and cleaned gases, a fourth gas main connecting the centrifugal washers with a source of use, means whereby the flow of 30 gases into each centrifugal washer is regulated and shut off, means whereby the inlet

and outlet openings to each cleaning fan is closed, and means whereby the flow of gases into and out of each scrubber is regulated and shut off. 35

5. A gas washing plant comprising a plurality of gas scrubbers, a plurality of cleaning fans, and a plurality of centrifugal gas cleaners, a gas supply main connecting a source of gas supply with the scrubbers, a 40 gas supply main connecting the scrubbers with the rotary fans, a third gas main connecting the fans with the centrifugal gas cleaners, said main also having connections leading to a point of use for the scrubbed 45 and cleaned gases, a fourth gas main connecting the centrifugal washers with a source of use, and a series of valves whereby flow of gases into and out of said several mains is regulated and controlled, said 50 valves being located and arranged to shut off the flow of gases into and out of each cleaning device while the others are being operated.

In testimony whereof, we have hereunto 55 set our hands.
